TYPEWRITING MACHINE

Filed June 15, 1928

UNITED STATES PATENT OFFICE

JESSE A. B. SMITH, OF STAMFORD, CONNECTICUT, ASSIGNEE TO UNDERWOOD ELLIOTT
FISHER COMPANY, OF NEW YORK, N. Y., A CORPORATION OF DELAWARE

TYPEWRITING MACHINE

Application filed June 15, 1928. Serial No. 285,525.

This invention relates to work-holders for cylindrical platens of typewriting machines, the main object being to provide means for conveniently and quickly inserting and positioning small stiff cards of special shapes.

In telephone-transmitting equipments it is customary to employ a card upon which is printed the number of the telephone. These cards have a variety of shapes. It is an object of the invention to provide means for typewriting the numbers upon the cards, one feature of the invention being an improved means for holding these exceptionally shaped cards and feeding the same on the round platen, and for typing many cards during one line of typing or one travel of the typewriter-carriage.

The device is of the front-insertion order, in which the work is inserted downwardly at the front of the platen. It is inserted downwardly into a work-holder that lies close to the front of the platen and extends from end to end thereof, and is fixed to the platen. This work-holder, or clip, has at its top edge an undercut extending to the depth of about a quarter of an inch, leaving a slight space between the work-holder and the platen into which the bottom edge of the card is thrust downwardly, the bottom of the cut serving as the bottom gage for the card and trueing the card relatively to the printing line.

To aid in presenting the card properly to the work-holder there is provided upon the platen-carriage a bar extending along the platen and separated a little therefrom sufficiently to allow the free insertion of the card downwardly behind the bar and in front of the platen, the bar and the platen co-operative to form a chute for the introduction of the work-piece downwardly into the card-clip. This chute-bar is stationary upon the carriage, not revolving with the platen but usefully holding the work back against the platen during the typing.

Preparatory to inserting a card, the platen is backed around until the card-holding clip thereon comes up close to the stationary introductory bar, and then the card is inserted, bottom edge first, between the introductory bar and the platen and descends into the

55 pocket of the clip-bar. The platen is then rotated backwardly, together with its clip and the card, to bring the proper point of the work to the printing line, and then the number is typed upon the card, the chute-bar and the clip co-operating to bend the card firmly against the platen, to give a good backing for the card for receiving the type-blows. While the card at first sets down loosely into the 60 pocket formed along the top edge of the clip-bar, still it will be understood that by turning the platen backwardly the clip operates to bend the card a trifle around the platen, and thereby a firm grip is secured upon the card, so that it is not in danger of becoming displaced during the typing operation. This grip increases with the backward 65 travel of the platen.

The typewriting machine may be provided with a set of exceptionally large types for 70 printing the numbers very plainly.

One of the advantages of the invention is that many cards can be placed side by side in position upon the platen and then, by turning the platen back, all the cards are dropped 75 to bring them to printing position. Then all of the cards can be typed during a single run of the carriage, and then all taken out preparatory to inserting a fresh quantity of cards.

80 Any kind of irregularly shaped cards can be inserted, and some of them are illustrated. The invention is also serviceable for the downward introduction of other work-pieces, such as envelopes and small sheets, and in all cases the advantage gained is the alignment of the work-piece relatively to the printing line without attention from the operator, who has only to press the work-piece down until it reaches the bottom of the pocket in the card-clip.

85 When writing a number of telephone number cards, the device can be employed that usually releases the platen from the control of the linespace wheel. The platen is then turned downwardly to bring the card into proper position for typing while the platen remains released. Then the platen is reconnected to the line-space wheel. Then when typing any 90 quantity of similar cards, it is only necessary 100

to insert the card and turn the platen backwardly for a given number of notches, whereupon the card will be brought automatically into proper typing position without adjustment of either the card or any part of the typewriter-carriage.

The device is useful for front or downward insertion of small stiff work-pieces. A work-clip is fixed upon the platen to be rotatable therewith and is normally located below the typing line. It is effective to hold and gage the lower extremity of a work-piece. A stationary member is rigidly mounted upon the platen-frame in close relation with the platen-surface above the typing line, to hold the upper part of the small work-piece down upon the platen. In this co-operative way a small stiff card is securely held and flexed back upon the front of the platen for a firm support at the typing operation.

In positioning a plurality of similar cards along the platen, a form of clip is preferred which extends from end to end of the platen, and has an undercut along its entire upper edge to receive and gage therein the lower extremities of a line of work-pieces. Above the typing line is a bar extending from end to end of the platen-frame. A plurality of cards may be introduced and positioned by a single sweep of the platen, the numbers written during one travel of the carriage, and the cards discharged again by returning the platen.

The stationary holding member may be adjustable upon the platen-frame to vary the clearance of the paper intake for proper co-operation with said clip when the work-pieces are being inserted.

Settable gages may co-operate with the holding device, to laterally locate the work-pieces in a predetermined manner along the platen, for co-operation with settable carriage-stops, to quickly position the work-pieces at the printing point.

The settable gages may form chutes arranged along the platen, by means of which a line of irregularly shaped work-pieces may be quickly positioned.

An ordinary tabulating mechanism successively brings the work-pieces to the printing point for a single-line entry thereon.

Other features and advantages will hereinafter appear.

In the accompanying drawings.

Figure 1 shows the novel work-holding device as applied to the platen and the carriage-frame, respectively, of a standard machine, a line of small cards being lined up in preliminary position along the platen and ready to be shifted simultaneously down to the typing line.

Figure 2 is a cross-section taken of Figure 1, and shows more clearly the procedure of inserting a plurality of small work-pieces, according to the novel method, whereby the

movable paper-clip is shown as shifted to proximity with the stationary bar or guiding member above the typing line.

Figure 3 is similar to Figure 1, parts being broken away, to merely indicate the final position of the work-pieces relative to the typing line.

Figure 4 is a cross-section of Figure 3, showing the means to hold the small and stiff work-pieces above and below the typing line upon the platen-surface, for a single-line entry.

Figure 5 is an enlarged diagrammatic section, showing conditions prevailing at the preliminary stage of inserting small stiff work-pieces, and disclosing that the lower end portion of the cards, while loosely seated behind the clip and the stationary member, is given a slight crosswise tension upon the platen-surface, so as to enable the work-pieces by friction to be carried down to the typing line when the platen is backed up, as shown in Figures 3 and 4.

Figure 6 shows in detail a work-piece of special shape, being of lower height than those shown in Figures 1 and 3, to indicate an occasion which requires a change in the setting by operating the line-space clutch.

The frame of the platen-carriage is indicated to include the sides 10 in which is journaled shaft 11 of an ordinary rotary platen 12. The projecting left-hand end of the platen-shaft is shown to carry a well-known line-space wheel 13 with the associated detent-member 14, as found in standard machines. The line-space wheel is shown in connection with a clutch or frictional line-space mechanism 15, such as is disclosed in the patent to Helmond 1,148,167, dated July 27, 1915. This clutch permits the line-space wheel to be disconnected from the platen-shaft, so that the platen may be freely rotated to adjust a work-piece thereon to a certain reference line, while the line-space wheel is held stationary by a usual detent roller 16 resiliently mounted upon the platen-frame. There is also shown, for purposes hereinafter to appear, a tabulating mechanism known in the art and indicated merely by plungers 17 liftable upon the stationary machine-frame, as at 18, to co-operate with settable stops 19, the stops 19 being settable upon the rack-bar 20 which normally forms part of the travelling platen-carriage.

The tabulating mechanism ordinarily serves to jump the carriage predetermined distances, to quickly position certain columns at the printing point.

The novel work-holding device is shown to be used for the preferred purpose of positioning a line of irregularly shaped cards, for instance number cards, such as are employed upon the mouthpieces of telephones. The entry is a single-line entry and may be

made upon all the cards during one run of the carriage.

The device travels with the carriage and includes a clip 20^a fixed upon the platen to be rotatable therewith and effective to hold the lower extremities of the work-pieces, and a stationary member rigidly mounted upon the platen-frame to hold the work-pieces above the typing line.

10 A preferred type of paper-clip or card-holder is shown substantially as disclosed in the patent to Lindburg, 1,600,235, dated September 21, 1926. The clip includes a bar 21 extending along the platen and curved 15 to fit the surface thereof. The bar at its upper edge has an undercut 22 of ample depth to receive and hold therein small front-inserted work-pieces, such as shown in the form of an envelope 23 (in dot and 20 dash), or in the form of a line of small number cards 24 and 25. As the work-pieces are thrust downwardly into said undercut, the bottom of the cut will serve as a bottom gage for the cards, and true the same relatively to 25 the printing line. The bar 21 is formed at each end with a side arm 26 having slots 27 to engage over flattened hubs 28 of the platen-shaft. A latch 29 is pivoted at 30 upon each side arm and has a hook 31 to embrace said hub to securely attach the card-holder to the platen. A finger-piece or lug 32 provided upon an opposite extension of 35 said latch serves to unlatch the card-holder from the hub. An arcuate slot 33 in the latch co-operates with a pin 34 upon the side arm to limit the movement of the latch. There are also shown another pin 35 upon 40 the latch, and a tension spring 36 hooked upon pin 34 and pin 35, respectively, to hold the latch against accidental release. The stationary part or intake of the work-holding device includes a bar 37 extending from 45 end to end of the platen-frame, and supported by brackets 38 at each end, said brackets being mounted upon the top of the sides 10 of the platen-frame and having depending portions 40 to locate said bar 37 above the typing line and in proximity to the platen-surface. Due to screw-and-slot 50 connections 39, 39^a between the brackets and the supporting platen-frame, the intake clearance may be altered to suit the character of the work-pieces, and for proper co-operation of the intake with the clip or 55 card-holder.

The novel card-handling method provides that the card-holder be turned upwardly with the platen (see Figure 2) to proximity with the stationary bar 37 to form there- 60 with a pocket or groove in which a line of cards, as shown at 24 and 25, is to be primarily seated and positioned.

The diagrammatical detail Figure 5 shows the lower extremities of the work-pieces in 65 slightly curved condition flexed upon the

platen while held in the arcuate undercut 22.

This slightly tensioned condition offers sufficient friction upon the platen-surface to subsequently carry the work-pieces down to the printing line when the platen is backed up in the direction of the arrow, as shown at 70 Figure 4, and when said work-pieces are pulled down under the guidance of said stationary bar 37. It will be understood that the grip upon the platen increases with the backward rotation of the platen, thereby securing a firm grip upon the card, so that the latter is not in danger of becoming displaced during the typing operation. Since said bar 37 is in fixed position upon the platen-frame 75 it will not move under the tension of the flexed stiff cards, and a type-bar 40^a will find a firm backing at the printing line.

From Figures 4 and 5 it will furthermore appear that the card-holding portions of the devices are spaced from the platen-surface and disposed relatively to each other, so as to allow the upper and lower ends of the cards to slightly flare away from the platen-surface, while the intermediate portions, due to 80 the stiffness of the cards, are tensioned upon the platen.

When writing a number of telephone cards, the above-mentioned clutch 15 can be employed. After releasing the platen from the control of the line-space wheel, the platen may be turned downwardly to bring the cards into proper position, when the platen may be reconnected to the line-space wheel. Now the card-holding device is so conditioned that when typing any quantity of similar cards it is only necessary to insert the cards and turn the platen backwardly for a given number of line-spaces, whereupon the cards will be brought automatically into proper typing 90 position without adjustment of either the cards or any part of the typewriter-carriage. It is also possible to use any other known means for predetermining the required 95 platen-sweep in order to facilitate and speed up positioning of the cards.

A further expedient in the present card-handling method provides side gages 41 setably mounted upon said bar 37 for each work-piece 24, 25. One pair of side gages 10 may form an individual chute for each work-piece, each gage having a slot-and-screw connection 42, 43 with said bar 37, so as to be laterally adjustable upon the bar to fit variable sizes of work-pieces, and particularly 110 to aid in positioning cards of irregular shape. At 44 are shown additional tapped holes upon the bar 37 to be used for a different set-up of 115 said gages 41.

According to another feature, the chutes or gages may be arranged and adjusted to laterally predetermine the location of each work-piece upon the platen in a manner to co-operate with a tabulating mechanism as mentioned above. After a series of work- 120 125 130

pieces 24, 25 is thus positioned at the typing line, the tabulating mechanism may be operated to successively bring each work-piece to the printing point. This combination adds to the time and labor saving qualities of the device.

Variations may be resorted to within the scope of the invention, and portions of the improvements may be used without others.

10 Having thus described my invention, I claim:

1. In a typewriting machine having a carriage including a platen-frame, the combination with a rotary platen, of means for positioning small relatively stiff work-pieces thereon for typing, including a paper-clip upon said platen rotatable therewith, to hold the lower extremity of a small work-piece, and a stationary member rigidly mounted 15 upon the platen-frame above the typing line and spaced from the platen-surface to allow free insertion of a work-piece and to hold the upper part of said work-piece flexed down upon the platen when rotated back- 20 ward.

2. In a typewriting machine, having a laterally traveling carriage including a platen-frame, and having tabulating instrumentalities, the combination with a rotary platen, 25 of means for quickly positioning small work-pieces at the printing point, said means including a clip engaged upon the platen to be rotatable therewith, and effective, by co-operating with the platen-surface, to hold the lower edge of front-inserted work-pieces, a stationary bar spaced from the platen and above the typing line mounted upon the platen-frame, and effective to hold the upper part of a work-piece down upon the 35 platen, and settable gages associated with said bar to laterally predetermine the position of a work-piece so that the tabulating mechanism may jump the carriage to position the work-piece at the printing point.

3. In a typewriting machine, having a laterally traveling carriage including a platen-frame, the combination with a rotary platen, 40 of means for quickly positioning a line of small irregularly-shaped work-pieces for typing the same during one travel of the carriage, said means including a clip engaged upon the platen to be rotatable therewith, and effective, by co-operating with the platen-surface, to hold and gage the lower extremity 45 of front-inserted work-pieces, a stationary bar spaced from said platen and mounted upon the platen-frame, to extend above the typing line parallel thereto, and effective to hold the work-pieces upon the platen, and 50 settable gages for the work-pieces mounted upon said bar so as to laterally confine the work-pieces thereon, said gages co-operative with said clip in properly positioning the work-pieces, said bar having a row of spaced holes, and said gages being arranged in pairs,

one pair for each card, each gage having a slot extending lengthwise of the bar, and individual fastening devices passing through said slots and anchored in said holes, for receiving the gages where adjusted.

4. In a typewriting machine, having a carriage including a platen-frame, the combination with a rotary platen, of a device for conveniently positioning a line of small work-pieces to be arranged along the platen 75 for typing the same during one travel of the carriage, said device including a clip fixed upon the platen and effective to grip and to seat the lower extremities of the work-pieces, a bar mounted upon the platen-frame above the typing line, and a pair of side gages for each work-piece, to be adjustably mounted upon said bar, to form individual chutes to fit the work-pieces to be inserted therein and to be seated when the clip is raised to proximity with said chutes at the initial stage of insertion, said work-pieces consecutively to be pulled by said clip downwardly through said chutes when the platen is backed up, to position the work at the typing line.
